PROCESS AND APPARATUS FOR OXIDIZING COMBUSTIBLE MATERIAL

Application filed June 22, 1931. Serial No. 546,066.

This invention relates to process and apparatus for oxidizing combustible materials to intermediate oxidation products, and more specifically to certain embodiments in temperature control of such oxidations and preparation of the reaction mixtures.

In the past, the vapor phase air oxidation of such combustible materials as aliphatic and aromatic hydrocarbons, phenols, alcohols, acids, esters and the like has been accompanied by many difficulties, both in control and maintenance of the temperature of the reaction and in the preparation of a suitable reaction gas mixture. Ordinarily such materials have been vaporized in the presence of air, either by passing an air stream through or over a liquid body of the material to be oxidized, maintained at suitably elevated temperatures, or by spraying or otherwise diffusing the material in finely divided form into a stream of air or other oxygen containing gas. Reaction mixtures so produced are often explosive, particularly when hydrocarbons such as naphthalene, ace-
25 naphthene, benzene, toluene or crude or purified anthracene are vaporized, for the amount of oxygen required by the reaction is such that a vapor well within the explosive limit is obtained. Moreover, since the vaporization
30 temperatures of many of these substances are quite high, great care must be taken to keep the reaction mixture from contact with any substance which will act as an ignition catalyst, and such substances as iron rust, con-
35 verter scale, or even the pyrolytic coke which tends to accumulate in the vaporizers and become entrained in the gas stream are always a source of fire danger.

The present invention provides a novel process and apparatus for overcoming these and other difficulties by an arrangement which at the same time provides a complete control of the course of the reaction during catalysis. It has been found that the temperature of the catalyst in the converters can be properly maintained by means of a non-boiling bath surrounding the catalyst tubes, heat given off by the reaction being transmitted through the bath to cooling elements 50 through which air or other gaseous media

are passed, and in my prior application Serial No. 448,410, filed April 29, 1930 the use of this cooling gas, suitably preheated by the bath, has been proposed for use in the vaporizers, which provides an excellent method of 55 utilizing the heat given off but does not in any way overcome the fire hazard.

According to the present invention, vaporization is effected entirely by means of steam or other non-oxidizing gases such as 60 carbon dioxide, nitrogen, stack gases and the like without the addition of oxygen or with the use of only such small amounts of oxygen as will not create a fire hazard. The material vaporized in this manner is then mixed 65 with air or other oxygen containing gas which has been preheated by heat exchange with the non-boiling bath just before the mixture is subjected to catalysis, thus avoiding the danger of explosions in the vaporizer 70 or the passage of an explosive mixture through any length of piping which might become oxidized thereby and produce a pyrolytic oxide. The invention also provides for the suitable regulation of the amounts and 75 temperature of the oxidizing air, in order to add flexibility to the process and enable its application to a wide range of materials.

The invention will be described in conjunction with the accompanying drawing 80 which shows diagrammatically two embodiments thereof, and in which

Fig. 1 represents a system designed for intensely exothermic reactions, such as the oxidation of naphthalene to phthalic anhydride, in which more air is needed to cool the converter than would be required to effect a satisfactory oxidation of the reaction mixture; and

Fig. 2 shows a system wherein all the air 90 necessary to control the bath temperature is used in forming the reaction mixture, this arrangement being suitable for less strongly exothermic reactions, such as the oxidation of anthracene to anthraquinone, acenaphthene to naphthalic anhydride and toluol to benzaldehyde and benzoic acid.

Referring to Fig. 1 of the drawing, the converter consists of a shell 1, with top and bottom pieces 2 and 3, upper and lower tube 100

sheets 4 and 5, and spaced catalyst tubes 6 in which catalyst is retained by the lower screen 7. The tubes are surrounded by a bath 8, which consists of material having a boiling point above the reaction temperature, such materials as lead, metal alloys such as mercury-lead or mercury-tin, or a eutectic mixture of sodium nitrate and sodium nitrite being suitable. Interspersed among the catalyst tubes and extending into the bath liquid are heat exchange tubes 9, adapted for the passage of air or other cooling gas in heat exchanging relation with the bath liquid. In the modification shown, these heat exchange elements are shown as telescoping, double countercurrent tubes, consisting of an inner, open end tube 10 and an outer, closed end tube 11. All the inner tubes 10 are connected together at their tops by means of a connecting manifold 12, which is in turn connected with inlet pipe 13 through which the cooling gases are admitted. In similar manner, the outer closed end tubes 11 are connected at their tops by the manifold 14, a continuation of which serves to lead the hot gases away from the converter shell.

The material to be oxidized in the converter is fed through inlet pipe 15 into vaporizer 16, where it is vaporized at suitably elevated temperatures by means of steam, CO_2 or other inert gases such as those issuing from the converter, after removal of partial oxidation products therefrom, the absence of any large amounts of oxygen permitting the use of any desired vaporizing temperatures without fire danger. Vapors from the vaporizer 16 are led to the converter through the pipe 17, in which there is also of course no danger of explosion. The air necessary for the vapor phase oxidation is taken from the outlet manifold 14 through the pipe 18, controlled by the valve 19, and is only admitted to contact with the vapors to be oxidized at the point 20 where the vapors are entering the converter and are subject to its temperature regulation. Excess air in the manifold 14 may be led through the tubes of a steam boiler as shown, where it serves to generate steam for the vaporizer 16, or may be applied to any other suitable purpose.

The above described system permits a close and exact regulation of the composition of the reaction mixture, for there is always an excess of preheated air ready for use and the vaporization is much more easily effected with steam or other inert gases since much higher temperatures can be used with safety.

In the modification of Fig. 2 a converter is shown which is similar in construction to that of Fig. 1, but means for a defined recirculation of the bath material are provided. These means consist of a vertical baffle 31 which is placed around the catalyst tubes 6 in order to provide, together with the converter shell 1, a cooling zone 32. The heat

exchange tubes 9 are placed in this cooling zone instead of being interspersed among the catalyst tubes, and the bath liquid is caused to travel through the zone and downwardly along the catalyst tubes in order to effect a more efficient heat exchange with the gas passing upwardly within them. For small converters a simple thermosiphon flow such as that indicated will be sufficient, but for larger installations it is advisable to provide a central well together with impelling means such as a propeller for positive recirculation of the bath liquid.

The air or gases of higher or lower oxygen content which is used for cooling the bath enters through the manifold 33 and is passed downwardly through the inner tubes of the double countercurrent heat exchange elements 9 into the lower portions of the outer tubes 10, where it passes upwardly in countercurrent to the downward flow of bath liquid outside the tubes and becomes heated thereby. The mixture of steam and vapors to be oxidized is admitted at 34 and is deflected by the baffle 35, thus bringing it into intimate admixture with the stream of heated air coming from the heat exchange tubes 10, the ends of which extend somewhat above the upper tube sheet 4 in order to produce a more intimate admixture. Additional air is admitted through the valve 36 if needed, thus adding flexibility to the system and permitting a close and exact regulation of the amount of air in the reaction mixture as well as providing an important means of cooling the reaction if for any reason an undue temperature rise is encountered. The mixture is then passed downwardly through the catalyst in the tubes 6, the product of the reaction leaving the converter through the outlet 37.

The modification of Fig. 2 provides a greatly simplified construction for only a single air manifold is required, the air from the outer heat exchange elements being mixed with the reaction vapors within the head space of the converter itself. It will be seen, however, that with either form of construction the objects of the invention are fully realized, for by introducing the oxidizing air either during entry of the vaporized material into the converter there is no fire danger and the entire amount of heat necessary to bring the vapors to reaction temperature is supplied by the exotherm of the catalytic reaction itself.

What is claimed as new is:

1. A process of oxidizing combustible materials, which comprises vaporizing the material with a gas containing insufficient oxygen to support combustion and adding an oxidizing gas to the vapors so formed just prior to contact with a catalyst.

2. A process of oxidizing combustible materials to intermediate oxidation products, which comprises maintaining an oxidation

- 5 catalyst in heat exchanging relation with a bath, vaporizing the material with a gas containing insufficient oxygen to support combustion and passing the vapors over the catalyst, passing an oxygen-containing gas in heat exchanging relation with the bath and admixing at least a part of it with the vaporized material just prior to contact of the latter with the catalyst.

10 3. A process of oxidizing combustible materials to intermediate oxidation products, which comprises maintaining an oxidation catalyst in heat exchanging relation with a bath liquid, causing recirculation of said liquid through cooling zones, vaporizing the material with a gas containing insufficient oxygen to support combustion, passing an oxygen-containing gas in heat exchanging relation with the bath liquid in said cooling zones, and bringing it into admixture with the vapors just prior to contact of the latter with the catalyst.

15 4. Catalytic apparatus comprising a converter having vertical, catalyst-containing tubes, a bath liquid in said converter and surrounding said tubes, heat exchange elements in said bath liquid for the passage of an oxygen-containing gas, a vaporizer, means for admitting a non-oxidizing gas to said vaporizer, an inlet connecting said vaporizer to said converter, and means for admixing oxidizing gas from the heat exchangers with the vapors from the vaporizer just prior to entry of the latter into the catalyst tubes.

20 5. Catalytic apparatus comprising a converter having catalyst-containing tubes, a bath liquid surrounding said tubes, heat exchange elements in contact with said bath liquid, means for admitting an oxidizing gas to said heat exchange elements, means for leading away the oxidizing gas from said heat exchange elements, a vaporizer, means for admitting a non-oxidizing gas to said vaporizer, an intake pipe connecting said vaporizer with said converter, and means for admitting oxidizing gases into said intake pipe from the outlet of the heat exchanger.

25 6. Catalytic apparatus comprising a converter having catalyst-containing tubes, a bath liquid surrounding said tubes, heat exchange elements in contact with said bath liquid, means for admitting an oxidizing gas to said heat exchange elements, a vaporizer, means for admitting a non-oxidizing gas to said vaporizer, means connecting the vaporizer with the inlet of the converter and means permitting the gas leaving the heat exchange elements to mingle with the incoming gases from the vaporizer.

30 7. Catalytic apparatus comprising a converter having catalyst-containing tubes, a bath liquid surrounding said tubes, heat exchange elements in contact with the bath liquid, said heat exchange elements including inner, open end tubes surrounded by outer tubes closed at their lower ends, means for admitting an oxidizing gas to the inner tubes of said heat exchange elements, a vaporizer connected to the inlet of said converter, means for admitting a non-oxidizing gas to said vaporizer, and means for bringing the gas from the outer tubes of said heat exchange elements into admixture with the vaporizer gas just prior to entry of the latter into the catalyst tubes.

35 8. Catalytic apparatus comprising a converter having catalyst-containing tubes set into an upper tube sheet, a bath liquid surrounding said tubes, heat exchange elements set into said upper tube sheet and in contact with the bath liquid, said heat exchange elements including inner, open-end tubes surrounded by outer tubes closed at their lower ends only and having their upper ends extending above said tube sheet, means for admitting an oxidizing gas to the inner tubes of said heat exchange elements, a vaporizer, means for admitting a non-oxidizing gas to said vaporizer, and a connection between said vaporizer and the inlet of said converter, a catalytic apparatus comprising a converter having catalyst containing compartments, a bath liquid surrounding said catalyst compartments, heat exchange elements in heat exchanging relation with said bath liquid, means for passing an oxygen containing gas through said heat exchange elements, a steam generator, connecting means for causing at least a portion of the gases exiting from the heat exchange elements to pass through the steam generator, connection from steam space of the steam generator to a vaporizer for combustible material, said vaporizer permitting direct contact of the steam with the combustible materials, an inlet header to the catalyst compartments, connection from the vapor to said inlet header, and adjustable means for causing a portion of the oxidizing gas passing from the heat exchange elements to the vapor generator, to pass into the inlet header for the catalyst compartments.

40 Signed at Pittsburgh, Pennsylvania, this 18th day of June 1931.
